TELEPHONE MAGNET SYSTEM

Application filed December 16, 1926. Serial No. 155,158.

My invention relates to telephonic apparatus, and particularly to amplifying telephones, loud speakers or radio speakers, utilized in connection with radio receiving apparatus.

In accordance with my invention, the electro-magnetic system comprises a plurality of spaced field yokes or frames, preferably permanently magnetized, having on opposite sides poles of opposite signs, with inwardly projecting pole pieces comprising overlying pole piece extensions between which is received the free end of a vibratory reed, armature bar, or the like, secured at its other end to the aforesaid yokes or frames or one of them.

Further in accordance with my invention, the aforesaid inwardly projecting pole pieces are bifurcated to form sets of facing pole piece extensions; one set of which, and preferably the set most removed from the point of attachment of the reed or armature bar to its supporting structure being brought into overlying relation, while the other set, in this case the one nearest the said point of attachment lies in a substantially common plane to provide a shunt path for the magnetic flux traversing lengthwise the vibratory reed or armature.

Further in accordance with my invention, the air-vibrating diaphragm or tympanum of paper, metal, or other suitable material, preferably of large area or diameter and preferably conical is supported solely by a member substantially non-flexible in a direction coinciding with the gravitational plane of the diaphragm and of relatively great flexibility in a plane at right angles to said gravitational plane.

Further in accordance with a preferred form of my invention, the aforesaid vibratile armature or reed extends axially of the coil or winding traversed by the sound-representing current, which coil or winding is suitably supported upon stationary parts such as

the pole piece extensions, preferably by separate members carried thereby and so constructed and arranged that lateral movement of the coil or winding with respect to the vibratile reed is prevented.

My invention resides in the system, apparatus and features of construction of the character hereinafter described and claimed.

For an understanding of some of the forms my invention may take, reference is to be had to the accompanying drawing in which:

Fig. 1 is a side elevational view of a telephone magnet system constructed in accordance with my invention.

Fig. 2 is a vertical sectional view taken on the line 2—2 of Fig. 1 looking in the direction of the arrows.

Fig. 3 is a vertical sectional view, partly in elevation, taken on the line 3—3 of Fig. 2 looking in the direction of the arrows.

Figs. 4 and 5 are vertical sectional views taken, respectively, on the lines 4—4 and 5—5 of Fig. 1, looking in the direction of the arrows.

Fig. 6 is a horizontal sectional view taken on the line 6—6 of Fig. 1 looking in the direction of the arrows.

Fig. 7 is an enlarged view similar to Fig. 6, partly in section, showing the coil and its supporting members.

Fig. 8 is an enlarged view, partly in elevation and partly in section, of the structure shown in Fig. 7.

Fig. 9 is a perspective view of a coil supporting member.

Fig. 10 shows an alternative coil arrangement which can be used with other parts as before described.

Referring to the drawings, there is illustrated a magnet system comprising the plate-like yokes or frames A, A, preferably duplicate in character and each cut away or recessed interiorly thereof to define a substantially rectangular opening. Disposed between the yokes A, A is the vibratile mem-

ber, reed or armature 1 on either side of which, adjacent one end thereof, is disposed a washer 2 of magnetic or non-magnetic material, preferably, however, non-magnetic in character as brass or the like, through which washers and the perforated end of reed 1 extends a bolt 3 or the like for holding the parts in assembled relation. To the end that the yokes A, A may be held in parallel relation or substantially so, at the end thereof removed from the bolt 3, there is provided the spacing washer 4, likewise either magnetic or non-magnetic in character, but preferably non-magnetic and of brass or the like, and whose thickness corresponds substantially with the combined thickness of reed 1 and washers 2. Passing through this end of frames A, A and washer 4 is the bolt 5, preferably corresponding with bolt 3.

Secured between the yokes or frames A, A by the bolts of screws 6 are the inwardly extending pole pieces 7, each of which is bifurcated to form the spaced pole piece extensions or end portions 8 and 9. The extensions 8 are offset in opposite directions and disposed in superposed or spaced relation for the reception of the free end of reed 1. The pole piece extensions 9 are not offset, as are the extensions 8, but are extended in suitable close relation to the edges of the reed 1 to thereby provide a shunt path for the magnetic flux threading through said reed by virtue of the coil or winding associated therewith and which is traversed by fluctuating voice or sound representing current, such as exists, for example, in the anode circuit of a detector or audio frequency amplifier as utilized commonly in radio receiving circuits.

While I prefer to offset the pair of pole extensions 8 which are adjacent the free end of the reed, the reverse arrangement of offsetting the pair 9 and keeping the pair 8 not offset and in close relation to the edges of the reed may also be used.

Referring to Fig. 9, there is illustrated for the aforesaid coil C a mounting or supporting member M, preferably of brass or other non-magnetic material. Member M comprises a relatively plane surface 10 terminating in the flange or angular portion 11, which, in turn, terminates in the portion 12 extending substantially parallel with surface 10 and from which the member 11 extends the portion 13 substantially at right angles with respect to both. Adjacent its other end, member 10 is offset as indicated at 10^a and the portion thus offset terminates in the flange or angular portion 14 provided with the angular extensions 14^a.

For supporting the coil C and holding the same in suitable spaced relation with respect to the reed 1, there are utilized two of the supporting members M. The pocket formed at the end of each member M by the

intersecting portions 11, 12 and 13 is fitted over a pole piece extension 8 in such manner that portion 11 engages that face of the extension 8 nearest the spaced extension 9 Fig. 5, while portion 12 overlies the outer pole piece extension face or that face parallel with and most removed from reed 1 Fig. 7 and portion 13 overlies the end of said pole piece extension. Accordingly, the plane surfaces 10 of each member M extend toward the pole piece extensions 9 substantially in the plane of their respective outer surfaces. However, since the offset portions 10^a of each member M extend toward each other, and since the flange 14 overlies the pole piece extensions 9, Fig. 1, it results that the offset portions 10^a constitute shoulders, each of which engages the face of a pole piece extension 9, Fig. 8. The coil C may be supported directly on the aforesaid members M but preferably there is interposed therebetween the layer or strip 15 of paper, cloth or the like.

The members M function primarily as a support for the coil C to hold the same in suitable spaced relation with respect to the vibratory end of the reed 1. Moreover, due to their construction lateral or transverse movement of coil C with respect to the reed 1 is prevented since portions 13 of members M, respectively, engage the ends of pole piece extensions 8 and the offset portions 10^a constitute shoulders disposed between the pole piece extensions 9. By utilizing the structure just described, lateral movement in either direction of both ends of coil C with respect to reed 1 is prevented.

The coil C may have its terminals 16, 16^a connected to binding posts 17, 17^a mounted in spaced relation on a member or plate 18 preferably held in place on a yoke or frame A by the aforesaid bolt or screw 5. Member 18 may be formed of suitable insulating material, as a phenol condensation product or hard rubber, but preferably comprises a fabric, as linen or canvas impregnated in a phenol condensation product.

As hereinbefore described, the reed 1 is clamped between the yokes A, A by the bolt or screw 3. Between this screw and the coil C and preferably extending through ears 19 of yokes A, A are the members or screws 20 and 21, each of which at its end engages an opposite face of the reed 1. Accordingly, only that portion of said reed to the left of the screws 20 and 21, Figs. 1, 3 and 6, partakes of pivotal movement. Aside from thus determining by their position the length of the pivotal action of reed 1, the screws 20, 21 have the added function that by adjustment thereof, the reed may be adjusted with respect to the coil C to vary the dimensions of the air gap between its free end and the adjacent faces of pole extensions 8.

The yokes or frames A, A are preferably permanently magnetized, having poles of op-

posite signs at opposite sides thereof adjacent or coinciding with the regions wherein are attached the pole pieces 7.

Extending laterally from the reed 1 is the member or bar 22, to which is secured the air-vibrating member, diaphragm or tympanum T.

Member 22 may be secured to reed 1 in any suitable manner, preferably, however, as illustrated by riveting a block 23 to the reed 10 and then riveting the block and member 22 to each other.

Likewise, the diaphragm T may be secured to the member 22 in any suitable manner. An example of a satisfactory type of construction, when the diaphragm T is conical, is illustrated in Fig. 6, wherein the apex of the cone is provided with a circular opening faced by the headed or turned portion of a conical member 24 of suitable durable material, as 20 aluminum or soft steel, disposed exteriorly upon the diaphragm T. Disposed interiorly thereof is the conical facing washer or member 25, preferably of hard steel or the like. 25 As shown, the inner portion of member 24 is turned or headed and encompasses the adjacent edges of the diaphragm T and member 25. Resting on the exposed face of the member 25 are the angularly disposed portions 30 of a supporting member or bracket 26 of steel or other rigid material comprising two legs which converge to form a pocket receiving the end of member 22. Passing through aligned perforations in the pocketed portion 35 of bracket 26 and the end of member 22 is a bolt or the like 27.

The angular portions of bracket 26, and members 24 and 25 may be rigidly united with the diaphragm T by utilizing a plurality of 40 rivets or the like 28, each headed on opposite sides of the diaphragm.

As described in my co-pending application, Serial No. 155,159, filed Dec. 16, 1926, the diaphragm or tympanum T should be of relatively large diameter, preferably upwards of six inches, and for both axial and transverse vibration is unrestricted throughout and free to vibrate at its periphery at the frequency and with the amplitude of vibrations transmitted through the cone from 45 its axis or center, whereat only it is secured or fixed to and comprehended in the vibratory system comprising in addition the vibratory reed 1.

Under such conditions, a feature of my invention resides in the interposition of a flexible connecting member between the vibratory reed or armature and the cone. Referring to Fig. 6, the pivotal movement of 50 reed 1 imparts to the end of member 22 a to-and-fro movement in a plane extending at right angles longitudinally of the yokes A, A. Should the connection between the vibratory armature and cone be non-flexible, 55 such, for example, as is constituted by the

rigid pin or bar of the prior art, the cone is given a transverse bodily to-and-fro movement with resultant distorted or imperfect sound reproduction.

A feature of my invention resides in the interposition of a flexible, rather than a non-flexible, member between the reed and cone. Such, for example, as the member 22 which is constructed of spring steel, phosphor bronze, or the like. Due to its flexibility, this member bends or flexes in a plane extending at right angles longitudinally of the yokes A, A and as a result, due to the inertia of the cone, little or no transverse bodily movement is imparted thereto.

Where, however, the cone is unrestrained throughout and free to vibrate at its periphery as described above, the aforesaid member 22 constitutes the sole support therefor, and, hence, should be relatively non-flexible in the direction coinciding with the gravitational plane of the cone so as to carry the weight without flexing or bending. By way of example, the member 22 is illustrated as of substantially greater breadth than thickness and, hence, the aforesaid result may be attained by so suspending the cone that the weight is carried in the direction of breadth rather than width.

To thus render the member 22 non-flexible in one direction does not result disadvantageously, because the vibration of reed 1 does not impart a to-and-fro movement to the end of member 22 in the direction in which the weight of the cone is carried.

As described in my aforesaid application, Serial No. 155,159 filed Dec. 16, 1926, the herein described magnetic structure having the diaphragm T suspended therefrom may be attached to a casing F, preferably by utilizing the same screws 6 that hold the pole pieces 7 with the yokes A, A. When the frame is constructed of magnetic material, the screws 6 should be of suitable non-magnetic material, as brass. In the event that casing F is constructed of non-magnetic material, the screws 6 may be of magnetic material, if desired.

The aforesaid pole extensions 9 constitute, in effect, a path shunting the path between pole extensions 8 for the magnetic flux induced in the reed 1. Where the extensions 9 are brought into overlying relation with respect to the reed 1, thereby providing two sets of pole pieces cooperating therewith, it has been found that distortion is introduced into the sound-reproducing system. This condition probably arises due to the fact that the reed is pivotally mounted and, hence, due to the different lengths of the air gaps at the sets of pole pieces spaced unequally from the pivot, the reed, in different regions thereof, is effected by different tractive efforts. By eliminating the tractive effect of pole pieces 9, the reed is attracted and repelled in but

one region, thereby promoting the faithfulness of sound reproduction.

It is evident that the extensions 9 could be kept in overlying relation to the reed if located at a substantially non-vibratile part of the reed such as its fixed portion, but I prefer the simpler construction shown.

The pole piece extensions 9 may be brought into such spaced relation with respect to the reed 1 as may be suitable or desirable. Merely by way of example it may be stated that excellent results have been obtained when the gap between each pole extension 9 and the reed 1 is of the order of 0.004 or 0.005 of an inch.

It shall be understood that the magnetic system herein disclosed may be utilized to actuate a diaphragm of any desired character, as for example one which has its periphery restrained from vibration. Further, the magnetic system herein disclosed may be utilized with other types of loud speaking telephonic apparatus, as, for example, in lieu of the magnetic systems disclosed in the prior application to Kent, Serial No. 32,875, filed May 26, 1925; Greswold, Serial No. 65,076, filed Oct. 27, 1925; or to myself and Richter, Serial No. 41,031, filed July 2, 1925.

It shall also be understood that the connecting member, as one having the function and character of the member 22 herein disclosed, may be beneficially utilized, when the actuating reed or armature therefor is pivotally or oscillatorily mounted, with any diaphragm or tympanum which is sufficiently unrestrained from free vibration that undesirable transverse vibration occurs. Particularly, a member of the character of the member 22 herein disclosed, either with or without the associated magnetic system, may be associated with the diaphragms disclosed in the aforesaid applications to Kent, Greswold, and to myself and Richter.

Instead of utilizing a single coil traversed by sound-representing current and surrounding the vibratile armature bar as hereinbefore described, I may utilize construction of the character illustrated in Fig. 10, or equivalent, wherein each pole piece extension 8 is shown as having disposed thereon a coil C² so connected that when one is helping the permanent magnet flux, the other is opposing it. Obviously, with the construction disclosed in Fig. 10, there may be utilized a single coil C² on but one pole piece extension, if found desirable. Moreover, instead of disposing the coils C² on the pole piece extensions 8, either or both of the pole piece extensions 9 may have a coil C² disposed thereon. Or a coil C² may be disposed on a pole piece extension 9 and another coil C² on a pole piece extension 8; or a single coil C² may be disposed on the pole piece extensions 8, 9 of a single pole piece 7.

What I claim is:

1. A telephone magnet system comprising permanently magnetized frames, pole pieces therefor extending from opposite sides of said frames, a flexible armature bar disposed between said frames, and means for securing said frames and armature bar in assembled relation as a unitary structure. 70

2. A telephone magnet system comprising spaced permanently magnetized frames, pole pieces therefor extending from opposite sides of said frames, a vibratile armature bar secured adjacent its one end to said magnet frames and having its free end disposed adjacent said pole pieces, and a member carried by one of said frames and coacting with said armature bar in a region removed from said one end thereof. 75 30

3. A telephone magnet system comprising spaced permanently magnetized frames, pole pieces therefor extending from opposite sides of said frames, a vibratile armature bar secured adjacent its one end to said magnet frames and having its free end disposed adjacent said pole pieces, and members carried, respectively, by said frames and extending toward each other into contact with opposite sides of said armature bar in a region removed from said one end thereof. 35 90

4. A telephone magnet system comprising spaced permanently magnetized frames, pole pieces therefor extending from opposite sides of said frames, a vibratile armature bar secured adjacent its one end to said magnet frames and having its free end disposed adjacent said pole pieces, and adjusting screws carried, respectively, by said frames and extending toward each other into contact with opposite sides of said armature bar in a region removed from said one end thereof. 95 100 105

5. A telephone magnet system comprising a magnet frame, a vibratile armature bar secured adjacent its one end to said frame, and bifurcated pole pieces forming pole piece extensions extending toward each other from opposite sides of said frame, one pair of said extensions overlying each other in spaced relation and embracing a free part of said armature bar, and another pair of said extensions extending toward each other throughout their length in substantially a common plane and terminating closely adjacent said armature bar. 110 115

6. A telephone magnet system comprising spaced permanently magnetized frames defining a substantially rectangular opening, a vibratile armature bar secured adjacent its one end between said frames and having its free end extending into said opening, and bifurcated pole pieces forming pole piece extensions extending toward each other into said opening from opposite sides of said frames, the pair of said extensions most removed from said one end of said armature overlying each other in spaced relation and 120 125 130

- embracing the said free end of said armature bar, and another pair of said extensions extending toward each other in substantially a common plane and terminating closely adjacent said armature bar.
5. 7. A telephone magnet system comprising a magnet frame, bifurcated pole pieces forming pole piece extensions extending toward each other from opposite sides of said frame, a winding traversed by sound-representing current, a vibratile armature bar coacting with a pair of said pole piece extensions and extending axially through said winding, and means comprising a plurality of duplicate non-magnetic members supported by said pole piece extensions and upon which said winding is disposed.
10. 8. A telephone magnet system comprising a magnet frame, bifurcated pole pieces forming pole piece extensions extending toward each other from opposite sides of said frame, a winding traversed by sound-representing current, a vibratile armature bar coacting with a pair of said pole piece extensions and extending axially through said winding, means comprising a plurality of duplicate non-magnetic members supported by said pole piece extensions and upon which said winding is disposed, said members being constructed and arranged to prevent transverse movement of said winding with respect to said armature bar.
15. 9. A telephone magnet system comprising spaced permanently magnetized frames defining a substantially rectangular opening, a vibratile armature bar secured adjacent its one end between said frames and having its free end extending into said opening, bifurcated pole pieces forming pole piece extensions extending toward each other into said opening from opposite sides of said frame, one pair of said extensions overlying each other in spaced relation and receiving said free end of said armature bar, and another pair of said extensions extending toward each other throughout their length in substantially a common plane, a winding through which said armature bar axially extends, and members maintained in spaced position by said extensions to support and position said winding.
20. 10. A telephone magnet system comprising spaced permanently magnetized frames defining a substantially rectangular opening, a vibratile armature bar secured adjacent its one end between said frames and having its free end extending into said opening, bifurcated pole pieces forming pole piece extensions extending toward each other into said opening from opposite sides of said frame, one pair of said extensions overlying each other in spaced relation and receiving said free end of said armature bar, and another pair of said extensions in close relation to said
25. 11. A telephone magnet system comprising spaced permanently magnetized frames defining a substantially rectangular opening, a vibratile armature bar secured adjacent its one end between said frames and having its free end extending into said opening, bifurcated pole pieces forming pole piece extensions extending toward each other into said opening from opposite sides of said frame, one pair of said extensions overlying each other in spaced relation and receiving said free end of said armature bar, and another pair of said extensions extending toward each other throughout their length in substantially a common plane and in close relation to said armature bar, a winding through which said armature bar axially extends, and means for supporting and preventing transverse movement of said winding with respect to said armature bar comprising a plurality of duplicate members, each of which comprises a pocket receiving a pole piece extension of said first-named pair, a shoulder disposed between the pole piece extensions of said second-named pair, and an angular portion engaging the outer faces of said second-named pair.
30. 12. A loud speaking telephone having a magnet system comprising a vibratile member, a diaphragm of large area and means for securing said diaphragm to said vibratile member comprising a member having substantially different flexibility in one direction than in another.
35. 13. A loud speaking telephone having a magnet system comprising a vibratile member, a conical diaphragm of large area, and means for securing said diaphragm solely adjacent its apex to said vibratile member comprising a member having substantially greater flexibility in one direction than in another.
40. 14. A loud speaking telephone having a magnet system comprising a vibratile member, a diaphragm of large area whose periphery is entirely free of restraint, and means for securing said diaphragm to said vibratile member comprising a member having substantially different flexibility in one direction than in another.
45. 15. A loud speaking telephone having a magnet system comprising an elongated vibratile member, a diaphragm of large area whose periphery is entirely free of restraint, and means for securing said diaphragm to said vibratile member comprising a member

having substantial flexibility only in a direction coinciding with the longitudinal axis of said vibratile member.

16. A loud speaking telephone having a magnet system comprising a vibratile armature, a diaphragm of large area, and a member extending laterally from said armature constituting the sole support for said diaphragm and substantially non-flexible in the gravitational plane thereof and of relatively great flexibility in a direction substantially at right angles to said plane.

17. A loud speaking telephone having a magnet system comprising a vibratile armature, a diaphragm of large area, and a member extending laterally from said armature of substantially greater breadth than thickness and constituting the sole support for said diaphragm, the breadth of said member coinciding with the gravitational plane of said diaphragm.

18. A telephone magnet system comprising a magnet frame, bifurcated pole pieces forming pole piece extensions extending toward each other from opposite sides of said frame, one pair of said extensions overlying each other in spaced relation, and another pair of said extensions extending toward each other throughout their length in substantially a common plane, a vibratile armature bar secured to said frame and in part received between said first named extensions and closely approached by said second named extensions, and a winding traversed by sound-representing current for vibrating said armature bar.

19. A telephone magnet system comprising a magnet frame, a vibratile armature bar rigidly secured adjacent its one end to said frame, and bifurcated pole pieces forming pole piece extensions extending toward each other from opposite sides of said frame, the pair of said extensions most removed from said one end of said armature overlying each other in spaced relation and receiving said armature bar at or adjacent its free end, another pair of said extensions extending toward each other throughout their length in substantially a common plane to regions closely adjacent said armature bar, and a winding traversed by sound-representing current through which said armature bar extends.

20. A telephone magnet system comprising a magnet structure, an armature bar vibrating in one plane only, bifurcated pole pieces extending from both poles of said magnet structure into close relation with freely vibratile portions of said armature bar, a pair of pole piece extensions of opposite polarity situated on opposite sides of said armature bar and in its plane of vibration, the other opposing pair of pole piece extensions also situated on opposite sides of said armature bar but in a plane at right angles to its plane of vibration, and a winding traversed

by sound-representing current surrounding any or all of said pole piece extensions or that portion of the armature bar which lies between the two pairs of pole piece extensions.

21. A telephone magnet system comprising a magnet structure, an armature bar vibrating in one plane only, pole pieces extending from both poles of said magnet structure and each divided into two pole piece extensions, one pair of said pole piece extensions of opposite polarity situate on opposite sides of said armature bar and in parallel close relation to freely vibratile faces thereof, the second pair of pole piece extensions of opposite polarity situate in close relation to non-vibratile surfaces of said armature bar, and a winding traversed by sound-representing current surrounding any or all of said pole piece extensions or that portion of said armature bar which lies between the one pair and the second pair of said pole piece extensions.

22. A loud speaking telephone having a magnet system comprising a vibratile member, a conical diaphragm of large area, a member passing freely through said conical diaphragm substantially at the apex thereof, out of contact therewith, and secured to said vibratile member on the convex side of said conical diaphragm, and means to attach said conical diaphragm to said member on the concave side thereof.

23. A loud speaking telephone comprising a large diaphragm capable of axial and transverse vibration, a magnet system, structure co-operating therewith and movable in accordance with current variations of audio frequency, and a member connecting said diaphragm to said structure having substantially greater flexibility in one direction than in another to effect substantially solely axial vibration of said diaphragm.

24. A loud speaking telephone comprising a large diaphragm capable of axial and transverse vibration, an actuating member therefore having components of motion axially and transversely of said diaphragm, and a member connecting said diaphragm to said actuating member having substantially greater flexibility in one direction than in another to transmit to said diaphragm substantially solely said axial component of movement of said actuating member.

25. A loud speaking telephone comprising a large diaphragm capable of axial and transverse vibration, a magnet system including an armature having components of motion axially and transversely of said diaphragm, and a flexible member of width substantially exceeding its thickness connecting said diaphragm to said armature to effect substantially solely axial vibratile of said diaphragm.

26. A loud speaking telephone having a magnet system comprising structure co-oper-

ating therewith and movable in accordance with current variations of audio-frequency, a conical diaphragm of large area and capable of axial and transverse vibration, a member passing through said cone substantially at the apex thereof secured to said structure and having substantially greater flexibility in one direction than in another to transmit substantially solely said axial component of movement of said structure, and means connecting said member to the concave side of said diaphragm.

RUSSELL T. KINGSFORD.
